UNITED STATES PATENT OFFICE.

JOHN F. O'CONNOR, OF CHICAGO, ILLINOIS, ASSIGNOR TO WILLIAM H. MINER, OF CHAZY,
NEW YORK.

PROCESS OF MAKING STOP-PLATES FOR DRAFT-RIGGING.

1,305,663.

Specification of Letters Patent. Patented June 3, 1919.

Application filed November 16, 1916. Serial No. 131,615.

To all whom it may concern:

Be it known that I, JOHN F. O'CONNOR, a citizen of the United States, residing at Chicago, in the county of Cook and State of Illinois, have invented a certain new and useful Improvement in Processes of Making Stop-Plates for Draft-Rigging, of which the following is a full, clear, concise, and exact description, reference being had to the accompanying drawings, forming a part of this specification.

My invention relates to improvements in process of making stop plates for draft riggings.

15 The object of this invention is to provide a novel and efficient process of forming pressed steel stop plates for railway car draft riggings.

20 In the drawing forming a part of this specification, Figure 1 illustrates the original blank from which the stop plate is formed. Figs. 2 and 3 are side and end elevational views of the blank as the same appears at the end of the first operation. 25 Fig. 4 is a side elevational view of the completed plate. Fig. 5 is a horizontal sectional view taken substantially on the line 5—5 of Fig. 4. And Figs. 6 and 7 are vertical sectional views taken on the lines 6—6 and 30 7—7, respectively, of Fig. 4.

In carrying out my improved process, I first take a rectangular blank A of the required dimensions and thickness. In the first step of the process, the blank is placed 35 between suitable dies which form upper and lower longitudinally extending grooves 10—10 throughout the entire length of the blank, and short end centrally located grooves 11—11, the ends 12 of the blank 40 being also slightly offset from the main portion 13 of the blank, as clearly indicated by the shading in Fig. 2 and the end elevational view shown in Fig. 3. For the next operation, the blank is then interposed be- 45 tween suitable dies which form a series of transversely extending grooves 14, 15, 16, 17 and 18 therein. The central bend 16 is made deeper than the end bends 14 and 18 so as to make the center post or stop 19 50 deeper than the main end stops 20—20. The bends 15 and 17, which are located half way between the bends 14 and 16 and 16 and 18,

respectively, are made somewhat shallower than the end bends 14 and 18, to thus provide the limiting stops 21—21 of lesser depth than any of the main stops. Either after the first step or simultaneously with or subsequent to the second step, the longitudinally extending grooves 10—10 are subjected to an expanding operation to provide the necessary riveting areas as indicated at 22 and 23, the former being at the ends of the plate and the latter intermediate the main and limiting stops.

By employing the above described process, I provide a stop plate for draft riggings which is of substantially uniform thickness throughout and has the necessary main and limiting stop shoulders, the plate being correspondingly strengthened and braced 70 against both longitudinal and transverse strains by means of the longitudinally extending grooves 10 and 11. While the grooves 10—10 extend across the faces of all the stops, nevertheless the same are located 75 sufficiently near the upper and lower edges of the stop plate so as to leave large wearing and bearing surfaces on the stops at the central portions thereof.

Although I have herein illustrated and 80 described what I now consider the preferred manner of carrying out the process, the same is merely descriptive and I contemplate all changes, including changes in the 85 sequence of the steps, that come within the scope of the claim appended hereto.

I claim:

The herein described process of making a stop plate for draft riggings which includes, taking a blank and providing the same with a plurality of longitudinally extending strengthening grooves throughout the entire length of the blank; expanding said grooves laterally at predetermined spaced points therein to provide riveting areas; and providing the blank with a series of spaced transverse bends to thereby provide stop shoulders extending transversely of the stop plate.

In witness that I claim the foregoing I 100 have hereunto subscribed my name this 11th day of Nov. 1916.

JOHN F. O'CONNOR.
